UNITED STATES PATENT OFFICE.

LEWIS L. TATUM, OF MILWAUKEE, WISCONSIN, ASSIGNOR TO THE CUTLER-HAMMER MFG. CO., OF MILWAUKEE, WISCONSIN, A CORPORATION OF WISCONSIN.

PRESSURE-GAGE.

1,119,203.

Specification of Letters Patent.

Patented Dec. 1, 1914.

Application filed August 25, 1911. Serial No. 645,924.

To all whom it may concern:

Be it known that I, LEWIS L. TATUM, a citizen of the United States, residing at Milwaukee, in the county of Milwaukee and State of Wisconsin, have invented new and useful Improvements in Pressure-Gages, of which the following is a full, clear, concise, and exact description, reference being had to the accompanying drawing, forming a part of this specification.

My invention relates to improvements in pressure gages and more particularly to gages in which contacts are provided to be engaged by the pressure indicating needle for controlling electric circuits.

It is one of the objects of my invention to so mount the contacts to be engaged by the pressure needle as to permit the dial plate to be provided with an opening of sufficient size to enable full inspection of the gage movement without the removal of any of the parts thereof.

A further object of my invention is to provide simple, durable and easily adjustable means for supporting the contacts to be engaged by the pressure indicating needle.

Various other objects and advantages of my invention will be hereinafter clearly and fully set forth.

For the purpose of disclosing the nature and characteristic features of my invention, I shall describe the gage illustrated in the accompanying drawing which embodies my invention in one form. It should be understood however, that my invention is not limited to the specific device illustrated, but is susceptible of various modifications.

In the accompanying drawings:—Figure 1 is a front elevation of the gage. Fig. 2 is a view similar to Fig. 1 with the cover and dial plate removed. Fig. 3 is a sectional view taken on line 3—3 Fig. 1. Fig. 4 is a sectional view taken on line 4—4 Fig. 2 and Fig. 5 is a side view of one of the stationary contacts and the ring carrying the same.

The gage selected for the purpose of illustration is provided with a casing of conventional form. The casing comprises a cylindrical box member 1 provided with an annular supporting flange 2 and with a glass cover 3 retained in position by a ring 4 threaded on to the portion 1. The gage movement including the pressure indicating needle 5 is mounted upon a metallic plate 6. The gage movement is of conventional form

and accordingly need not be specifically described herein. The plate 6 is in turn mounted upon an insulating supporting base 7, said base being suitably secured to and supported by the support 8 of the Bourdon tube 9. Extending from the tube support 8 is the usual connection pipe 10. The tube 9 is preferably connected to the gage movement through an insulating member 11. With this arrangement it will be seen that the gage movement and tube are effectually insulated from one another.

Suitably arranged within the casing is a dial plate 12. In practice this dial plate may be secured in place in various different ways. I prefer however to mount the same in a manner hereinafter set forth. The dial plate 12 is preferably of annular form with a central opening of sufficient size to permit thorough inspection of the gage movement therethrough. The dial plate is provided with the usual graduated scale 13 preferably stamped therein.

The dial plate 12 is preferably formed of insulating material and of sufficient thickness to permit of the formation of two annular grooves 14 and 15 on the inner periphery thereof. The grooves 14 and 15 are provided for the reception of expansion rings 16 and 17 respectively which may be conveniently formed of resilient wire bent into a substantially circular form as shown in Fig. 5. In practice however, I form each ring of somewhat larger diameter than its corresponding groove so that when placed in its groove it will exert a pressure against the walls thereof. This pressure which is largely augmented by pressure against either end of the wire forming the ring effectually holds the ring against slipping in its groove. On the other hand if the rings be slightly contracted as by drawing the ends thereof together they may be readily slipped around or turned in their grooves. For facilitating this contraction of the rings the extremities 18 of the wires forming the same may be bent inwardly as shown in Fig. 5 so as to project out of the grooves and thus be easily grasped.

The rings 16 and 17 are provided for the support of contacts 20 and 21 respectively. In practice the contacts 20 and 21 may be of any preferred form and mounted upon the rings 16 and 17 in any preferred manner. I prefer however, to make these contacts of

a cylindrical form and to mount the same upon one of the extensions 18 of its supporting ring. Also I prefer to mount said contacts eccentrically on the extensions 18 as 5 illustrated in Fig. 3 so that a portion of each contact will project into the path of the gage needle. Further I prefer to provide the gage needle and stationary contacts with silver engaging portions. As illustrated I 10 have shown the needle provided upon opposite sides of its extremity with circular silver contact tips 22 and the contacts 20 and 21 with silver bands 23 encircling the same.

With the rings 16 and 17 mounted as 15 above described in the insulating dial plate, it is obvious that the same are thoroughly insulated from one another and may be placed in close proximity without danger. It will also be perfectly obvious that either 20 of the contacts may be readily moved to any desired position relative to the scale by merely contracting and turning its supporting ring, and that when the ring is released it will frictionally lock its contact in the desired position.

The electrical connections for the contacts and the needle may be made in various ways, but in practice I prefer to make them as follows:—I provide on one side of the casing 30 terminal devices 25, 26 and 27. These terminal devices may be of any preferred construction. As illustrated each comprises a bolt 28 passing through the casing and insulated therefrom by an insulating bushing 35 and insulating washers 30 and 31. The bolt 28 carries at its outer end a binding screw 32 for external connection, and at its inner end a conducting angle plate 33. The middle terminal device 26 is intended for 40 electrical connection to the plate 6 carrying the gage movement, this connection being made by a conducting strip 35 connected at one end to the angle plate 33 of the terminal device 26 and at its other end to the plate 6. 45 The terminal devices 25 and 27 are intended for electrical connection to the contacts 20 and 21 respectively. These connections are preferably made through thin conducting strips 36 and 37 placed in the bottom of the 50 grooves 14 and 15 respectively to be engaged by the rings 16 and 17 respectively. The strips 36 and 37 preferably extend all the way around these grooves to insure good contact between the same and their respective rings in all positions of the latter. The 55 conducting strips are then connected to the terminal devices. As illustrated in Fig. 3 the conducting strip 36 is electrically connected to terminal device 25 by a conducting strip 38 passing through the dial plate. As shown in Fig. 4 a similar connection is made between the conducting strip 37 and the terminal device 27 through the medium of a connecting piece 39. With this arrangement 60 when the gage needle 5 engages contact

20 it connects terminal devices 25 and 26 and when it engages contact 21 connects terminal devices 26 and 27.

Besides serving as electrical connections the angle plates 33 of the terminal devices 25 70 and 27 also serve as a convenient means of support for the dial plate. The dial plate may be readily secured to these angle plates as illustrated in Figs. 3 and 4 by screws 40, said screws also serving to secure the connecting pieces 38 and 39 to their respective angle plates. In practice it is preferable to secure the dial plate at at least one more point, and for this purpose a lug 41 (Fig. 2) is formed inside of the casing, the dial 80 plate being secured to this lug by a screw 42 (Fig. 1). While this is the preferred way of supporting the dial plate said plate may obviously be supported in various other ways.

What I claim as new and desire to secure by Letters Patent is as follows:—

1. A pressure gage provided with an annular dial plate, a pressure indicator movable within the central opening of said dial plate and contacts mounted upon the inner periphery of said dial plate and projecting into the path of said indicator to be engaged thereby in an abutting manner.

2. A pressure gage provided with an annular dial plate, a pressure indicator, and contacts adjustably mounted upon the inner periphery of said dial plate to be engaged by said indicator.

3. A pressure gage provided with a contact supporting member having annular grooves therein, expansion rings within said grooves for frictionally engaging the walls thereof, and contacts carried by said rings.

4. A pressure gage provided with a dial 100 plate, a pivoted pressure indicator, said dial plate having annular grooves therein concentric with the pivot of said indicator, expansion rings mounted in said grooves to frictionally engage the walls thereof, and contacts carried by said rings to be engaged by said indicator and to be adjusted to different positions by rotation of said rings.

5. A pressure gage provided with a pivoted pressure indicator, an annular dial 115 plate concentric with the axis of said indicator, revoluble rings mounted side by side on the inner periphery of said plate, and contacts carried by said rings to be engaged by said indicator.

6. A pressure gage provided with a pivoted pressure indicator, an annular dial plate concentric with the axis of said indicator, revoluble rings mounted side by side on the inner periphery of said dial plate, and contacts carried by said rings to be engaged by said indicator, said rings tending to expand to frictionally hold the same against movement.

7. In a pressure gage in combination, a

5 pivoted pressure indicator, an annular indicating dial, said dial having a pair of parallel grooves on the inner periphery thereof, expansible rings mounted in the 10 grooves in said dial plate, and contacts carried by said rings to be engaged by said pressure indicator.

10 8. In a pressure gage in combination, an insulating dial plate having a central opening for permitting full inspection of the gage movement without removal of any of the parts of the gage movement and contacts adjustably mounted upon said dial plate and disposed within said central opening.

15 9. In a pressure gage in combination, an annular insulating dial plate having parallel annular grooves in the inner periphery thereof, conducting strips within said 20 grooves, expansion rings within said grooves and in contact with said conducting strips, and contacts carried by said expansion rings to be engaged by a moving part of the gage movement.

25 10. In a pressure gage in combination, an annular insulating dial plate having parallel annular grooves in the inner periphery

thereof, conducting strips within said grooves, expansion rings within said grooves and in contact with said conducting strips, 30 contacts carried by said expansion rings to be engaged by a moving part of the gage movement, a plurality of terminal devices mounted upon the casing of the gage and insulated from one another and electrical 35 connections between the gage movement and one of said terminal devices and between the conducting strips in said grooves and either of said terminal devices.

11. A pressure gage provided with a pressure indicating device, an annular dial plate, members mounted upon the inner periphery of said dial plate, said members being movable at will around the inner periphery of said plate and being self-locking, and contacts carried by said members to be engaged by said indicator.

In witness whereof, I have hereunto subscribed my name in the presence of two witnesses.

LEWIS L. TATUM.
